COIL WINDING DEVICE

Oliver J. Luke, St. Louis, Mo., assignor to Carter Carburetor Corporation, St. Louis, Mo., a corporation of Delaware

Application October 29, 1945, Serial No. 625,281

8 Claims. (Cl. 242—13)

1

This invention relates to holding devices for wires or cords which must be held taut during such manipulation of the wire or cord as the winding of coils.

Coil winding machines, particularly for small motor armatures, are provided with hooks or pins conveniently located to receive a coiled end of the wire being wound and hold the wire taut during manipulation. However, at the end of the winding, it is necessary for the operator to unwind or pull the wire from the pin or hook and this is difficult where very fine wire is used.

The object of the present invention is to provide such a holding element for the end of a wire or cord being manipulated together with means for quickly and conveniently sweeping or casting off the wire from the pin at the end of the winding operation.

This object and other more detailed objects hereafter appearing are attained by the device illustrated in the accompanying drawing in which

Fig. 1 is a side view of a coil winding machine embodying a holding device according to the present invention.

Fig. 2 is an enlarged perspective view of the holding device.

Fig. 3 is a longitudinal section of the device.

Fig. 4 is a view similar to Fig. 3, but showing the wire pushed off its holding pins.

The coil winder in Fig. 1 comprises a motor 6 which drives a shaft 7 supported at its outer extremity by a journal bearing 8 carried on framing projection 9. Mounted intermediately of the shaft is a winding device 10 for motor armatures, this device being of known construction. Mounted on the device and carried therewith is the holding device 11 to which a wire 12 may be attached for holding the wire taut while the shaft is rotated to wind the coil.

The holding device, best shown in Figs. 2, 3, and 4, comprises a base 15 having a pair of permanently mounted pins 16 and 17 projecting laterally therefrom. The base also has a pair of countersunk holes 18 and 19 through which slidably extend a pair of rods 20 and 21. A strip or push-off element 22 is rigidly secured to the left-hand extremities of rods 20 and 21 and has a pair of holes slidably receiving pins 16 and 17. An actuator plate 23 is rigidly attached to the opposite ends of rods 20 and 21. Coiled springs 24 and 25 are compressed between the countersunk portions of recesses 18 and 19 in the base and plate 23 and normally maintain the push-off device in the position shown in Fig. 3 with plate element 22 at the inner extremities of the pro-

jecting portions of pins 16 and 17 and plate 23 spaced outwardly of the base member. An additional wire holding pin 29 projects longitudinally from base 15 and has a sharp edge 29a.

5 In operation, at the start and during the progress of the winding, wires 26, 27, and 28 are intermediately looped about pins 16 and 17, thence passed between guides 30 of the winding machine. The extreme end of wire 28 is coiled about pin 10 29 and edge 29a used to break off excess wire.

After the coil is completely wound, the operator strikes actuator plate 23 to move it and push-off plate 22 to the position shown in Fig. 4 which sweeps the wire loops from pins 16 and 17 and 15 also pulls the end of the wire from pin 29. This leaves the ends of the various coils free for attachment as by soldering to the commutator bars. Since actuator plate 23 is relatively large and the wires may be released from their holding pins 20 simply by striking the push-off member, this operation is much simpler and faster than would be the case where the operator must embrace the small pin and wire loops with his fingers to pull them off with the holding pins.

25 Obviously, the number of holding pins may be varied in accordance with the particular requirements of the winding machine. The invention may be modified in this and other respects as will occur to those skilled in the art and the exclusive 30 use of all modifications as come within the scope of the appended claims is contemplated.

I claim:

1. A wire or cord holding device comprising a base, a pin projecting therefrom for attachment 35 of a wire or cord, and a push-off element slidably mounted on said pin, said element being actuatable outwardly of said pin to force the cord or wire therefrom.

2. A wire or cord holding device comprising a 40 base, a pin projecting therefrom for detachably holding a wire or cord, and a push-off element having a recess slidably receiving said pin, said element having projecting structure actuatable to move said element outwardly along said pin and 45 detach a cord or wire therefrom.

3. A wire or cord holding device comprising a base, a pin projecting therefrom for detachably holding a wire or cord loop, and a push-off element comprising a part separate from said base 50 and slidable on said pin and actuatable outwardly thereof to detach the wire or cord loop therefrom.

4. A wire or cord holding device comprising a base, a pin projecting therefrom for detachably holding a wire or cord loop, a push-off element 55

comprising a part separate from said base but slidable on and actuatable outwardly of said pin to detach a wire or cord loop therefrom, and means yieldingly maintaining said part inwardly of the wire or cord loop receiving portion of said pin.

5. A wire or cord holding device comprising a base, a pin projecting therefrom for detachably receiving a wire or cord loop, and a push-off member comprising a pair of parts on opposite sides of said base, and a connecting element between said parts slidable in said base, one of said parts embracing and being slidable along said pin and the other part being disposed for manual actuation to sweep a wire or cord loop from said pin. 15

6. A device as described in claim 5 further including spring means normally maintaining said push-off member with said first part spaced inwardly of the coil receiving part of said pin and said second piece spaced outwardly from said 20 base.

7. A device for detachably holding the end of a wire or cord during manipulation of the wire or cord comprising a base, a pin projecting therefrom about which the wire or cord may be wound, a push-off member comprising a part having a hole slidable on said pin and a guiding element slidable in said base member, and spring means normally maintaining said push-off member with said part spaced inwardly of the wire or cord receiving part of said pin and said element projecting beyond said base for actuation by the operator to cause said piece to sweep said wire or cord from said pin.

8. A device as described in claim 7 in which said push-off member has a pair of elements slidable through said base, said elements being connected by a striker plate on the opposite side of said base from said element.
